US0D1048765S

(12) **United States Design Patent** (10) **Patent No.:** **US D1,048,765 S**
(45) **Date of Patent:** **** Oct. 29, 2024**

(54) **CUSHION**

(71) Applicant: **HAIKOU LILI INVESTMENT CO., LTD.**, Haikou (CN)

(72) Inventor: **Junyu Chen**, Haikou (CN)

(73) Assignee: **HAIKOU LILI INVESTMENT CO., LTD.**, Haikou (CN)

(**) Term: **15 Years**

(21) Appl. No.: **29/840,776**

(22) Filed: **May 31, 2022**

(30) **Foreign Application Priority Data**

May 25, 2022 (CN) 202230311196.1

(51) **LOC (14) Cl.** **06-09**

(52) **U.S. Cl.**

USPC **D6/601**

(58) **Field of Classification Search**

USPC D6/595, 596, 601, 604, 605, 611, 716.1

CPC A47C 27/00; A47C 27/001; A47C 17/18;

A47C 17/14; A47C 17/207; A47C 27/08;

A47C 27/144; A47C 27/146

Primary Examiner — Sanjeev Paul

(57) **CLAIM**

The ornamental design for a cushion as shown and described.

DESCRIPTION

FIG. 1 is a perspective view of a cushion showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.
